[57] **CLAIM**

The ornamental design for a magnetic disc recording/reproducing apparatus with semiconductor memory card recording/reproducing device, as shown and described.

DESCRIPTION

FIG. 1 is a perspective view of a magnetic disc recording/reproducing apparatus with semiconductor memory card recording/reproducing device showing our new design; FIG. 2 is a front view thereof;

FIG. 3 is a rear view thereof;

FIG. 4 is a top view thereof, the bottom view being an inverted image of the top view;

FIG. 5 is a right side view thereof; and,

FIG. 6 is a left side view thereof.
